PUMPING APPARATUS

Arthur John Adams, Trowbridge, England

Application August 24, 1940, Serial No. 354,057
In Great Britain November 22, 1938

4 Claims. (Cl. 103—203)

This invention relates to pumping apparatus comprising a positive displacement pump of the oscillating piston type and has for its object to provide improvements therein.

Now in accordance with the present invention I provide pumping apparatus comprising a pump of the oscillating piston type, a suction tank formed on the inlet side of the pump from which liquid is pumped to a delivery tank for the purpose of forming a seal to the valves, means being provided so that no air is passed through the pump until the suction tank is empty, and then the air is pumped through the liquid which at that time is transferred to the delivery side of the pump.

15 I may also provide suction breaking means.

The said means may comprise a suction breaking pipe so arranged and adapted to operate that the pump first delivers a quantity of liquid to air-seal all valves and the suction-breaking pipe 20 and then delivers all the air in the system through that liquid.

The apparatus may comprise a pump, an inlet container or tank and a delivery container or 25 tank with which the said pump communicates (the delivery tank may be the usual delivery pipe with slight modification), and a substantially U-shaped channel or pipe communicating with the inlet tank and which may be adapted 30 to be attached to a suction main, and means whereby the said U-shaped channel or pipe is adapted to retain and define the pre-determined height of the liquid to be used for priming the pump.

35 The accompanying drawings illustrate three forms of device, by way of example, made in accordance with the present invention as applied to means for pumping water.

Fig. 1 is a part sectional side elevation of one 40 form, and

Fig. 1a is a fragmentary detail showing an end of a by-pass pipe used in this form.

Fig. 2 is a section on the line 2—2 of Fig. 1.

Fig. 3 is a part sectional side elevation of another form and Fig. 4 is a front sectional elevation thereof;

Fig. 5 illustrates a modification in part sectional elevation.

In the form of device illustrated in Figs. 1 and 50 2, an oscillating piston pump 1 is mounted on the top of an inlet tank or container 2 and an inlet pipe 3 extends downwardly inside said tank 2 to a point adjacent to the bottom 4 of the tank. The inlet pipe 3 to the pump 1, thus disposed 55 inside the inlet tank 2 or container, is provided

with one or more air-ports 5, which ports are adapted to pass air to the pump 1 when a given amount of liquid has been passed by the pump, as hereinafter described. To this tank or container 2 is attached one inturned end 6 of a limb 8 of an inverted substantially U-shaped pipe 8, the remainder of said limb 8 extending upwardly parallel to the axis of the inlet pipe 3. The bend 9 of the U-shaped pipe 8 can be conveniently above the centre of the pump 1 and the free limb 10 10 of the U-shaped pipe extends down the back of the pump parallel to the axis of the inlet pipe, and it is adapted to be connected with a suction main. The U-shaped pipe 8 forms part of the tank 2 in this respect, that it retains and 15 defines the predetermined height of the liquid to be used for priming. Near the top of the U-shaped pipe 8 is disposed a filling plug 11 for said pipe. A suction-breaking pipe 12 is provided which sets up communication between the delivery and the suction side of the pump 1 and consists of a pipe or duct calibrated at one section 13. The word calibrated is used in connection with a short length of slot 13a in the pipe, the dimensions of which are arrived at by 20 25 the speed at which it is required to break the suction, thus if a very small slot were used, the suction would take longer to break and would become more likely to become choked with sediment. Therefore the largest slot consistent for 30 both purposes is used.

The pipe or duct 12 is covered with gauze 14 on the delivery side of the pump, and so arranged that it returns liquid to the suction tank 2. It is provided with a hand-operated valve 12a for 35 use when the pump is delivering under considerable pressure or an ordinary ball tap is incorporated in the delivery tank which cuts off communication otherwise than by the valves between the two tanks when the delivery tank fills. This 40 is necessary only when the maximum delivery is essential as, in ordinary practice, free communication with its slight loss through the suction breaker is not felt, as a considerable gain in delivery is obtained owing to the absence of a foot 45 valve with its obvious obstruction to the flow. The delivery tank 15 is of a size adapted to receive and contain all the liquid delivered by the pump 1 until the air-ports 5 in the inlet pipe 3 are free to pass air.

50 In operation the device is primed manually or by the pump by first delivering into the delivery tank 15 a quantity of liquid, e. g. water, substantially sufficient to cover the gauze 14 and so to make an air-seal. At all times the first 55

few strokes of the pump 1 will raise sufficient liquid from the inlet tank or container 2 to cover the suction breaking pipe 12 in the delivery tank 15 with liquid, thus forming the air-seal. The 5 inlet ports 5 of the inlet pipe 3 are then free to pass the air from the suction main. All air from the suction is pumped through with the water in the pipe 8 until the system is completely filled. Thus liquid is quickly raised to the inlet tank, 10 the pump, and so forth.

When the operation of pumping has been completed, the air pressure forces the liquid back through the pump.

When the strainer or gauze 14 on the suction-breaking pipe 12 is above the liquid level, the suction is broken immediately in the suction main, thus leaving the liquid level controlled by the U-shaped pipe 8 for repriming. The liquid at all times when the pump 1 is not in use remains at a level not far below the junction of the suction-breaking pipe 12 with the top of the U-shaped pipe 8.

For water, the tanks or containers may be relatively small, holding about 1½ pints, and 25 the time taken to lift 15 ft. may be 15 seconds, or to lift 25 ft. 20 seconds for a pump of approximately 1" suction main.

It is advantageous to form pump and tanks in one casting and they can be so constructed 30 that a pump can be installed to take the place of existing pumps without alteration of existing pipe work. Such a construction is illustrated in Figs. 3 and 4.

In the form of the invention illustrated in Figs. 35 3 and 4, there is provided a single unit arrangement where the priming apparatus is in one casting with the pump. In this case the housing 16 of the oscillating piston pump 17 is extended to 40 form an inlet tank 18 in which is situated the inlet stand pipe 19 with an open top 20 near the top of the tank 18. The inlet pipe is screw-threaded at 21 and forms a support or stand for the tank 18 and pump 17. The tank 18 and pump 17 are screwed on to the pipe 19 and suitably secured in position by nuts 22. The rocker or oscillating piston member 23 of the pump is carried by a spindle 24 of which one end 25 rocks in a bearing 26 in the wall 27 of the housing 16, the other end 28 of the spindle being adapted to 50 be driven by suitable driving means. The bearings of the ends of the spindle 24 are supported by a bracket 29 fixed to the housing 16 and straddling the inlet port 30 of the pump, provided at the bottom of wall 27. The side walls 55 31 of the bracket 29 cut off the pump chamber 32 from the inlet port 30 and are provided with flap valves 33 giving access to the said chamber 32. The rocker 23 is also provided with flap valves 34 giving access to the delivery tank 35. 60 A suction-breaking pipe 36 is disposed transverse to the pump chamber 32, substantially in the plane in which lie the spindle 24 and the longitudinal axis of the tank 35 and on a plane above the open end 20 of pipe 19. One end 37 of the 65 pipe 36 is hollow and is externally screw-threaded, and is adapted to be screwed into a correspondingly threaded socket 38 in the wall 27. The other end of the pipe 36 is closed and elongated and provided with a screw-driver neck 70 39 and is adapted to fit into a bush 40 disposed in a socket 41 in the wall 42 of the pump housing. The socket 41 is screw-threaded at its outer end for the reception of a plug 43. The pipe 36 is provided with lateral holes 44, and is covered 75 with gauze or perforated copper 45. The pump

housing 16 is provided with external fixing lugs 46 and the delivery tank 35 is provided with an outlet pipe 47. A drain-hole 48 is provided in the housing 16.

In use, the inlet pipe performs the function of 5 the U-tube in the previous example.

The water-seal is pumped up to the delivery tank 35 by the first two or three strokes of the pump, through a substantially U-shaped path between the end 20 of pipe 19 and the delivery tank 35, and during this process water is delivered back to the inlet tank 18 by the suction-breaking pipe 36, and continues to be so delivered throughout the operation of priming. Air at no time is drawn through the suction-breaking 15 pipe 36 by the pump. When the suction operation is finished and the suction breaker is no longer submerged atmospheric air passes through the pipe end 37 to the inlet tank 18 and prevents any siphoning action and so maintains the correct level for repriming.

When the pump is working, the suction-breaking pipe 36 is continuously washed on each side by the delivery, first on the right-hand side and then on the left, virtually eliminating all chance 25 of sediment choking the strainer 45.

The delivery tank 35 provides an effective water or liquid seal to all the valves and the inlet tank 18 provides the liquid for so doing at the first three strokes of the pump. When the operation of pumping is complete, the liquid in the delivery tank 35 flows back through the pump to a predetermined level, when air is admitted to destroy the partial vacuum and retain sufficient liquid to reprime the system when required. 35

In a modified form of device the suction-breaking tube 36 may be provided with a ball tap or valve such as is shown at 12a in Fig. 1, which can be conveniently arranged in the delivery tank 35, to eliminate the continuous by-passing 40 of water back to the suction side of the pump during the pumping operation.

The drawings show the suction breaker so arranged that the inlet side of the pump and the delivery side are at all times in free communication and when a hand operated needle valve is employed they are only in communication at the will of the operator and when a ball valve is incorporated communication is cut off when the delivery tank is full. 50

In case of frost a pump as above described is free from fracture due to the expansion of the ice as, at all times, the pump is left slightly more than half full of water due to the height of the standpipe in the inlet tank. In the event of 55 frost the ice rises in bulbous form in the inlet tank and also pushes its way through the valves in the pump body, and by this means the pump is free from fracture.

It will be understood that details of the system 60 may be varied in many ways without departing from the scope of the invention.

I am aware that in types of positive displacement pump other than the oscillating piston type, it has previously been proposed to provide a 65 suction tank formed on the inlet side of the pump from which liquid is pumped to a delivery tank for the purpose of forming a seal to the valves.

When it is desired to provide a continuous flow 70 in the form of a jet, as illustrated in the modification shown in Fig. 5, I extend the delivery pipe 47 down at 49 into the delivery tank 35, so as to form an air-bottle 50, and provide a comparatively restricted orifice 51 to the discharge 75

end 52 of the pipe and so obtain the desired continuous jet when the requisite power is applied to the pump.

For example, if the delivery pipe 47 be about 5 1" in diameter I provide a restricted orifice 51 about $\frac{5}{16}$ " in diameter. With ordinary speed of pumping there will be a discharge jet having a trajectory of approximately 20 feet which is of course increased or diminished according to the 10 speed of the pump. This is useful as a fire jet, or for window-cleaning and the like. It is applicable to Figs. 1 and 2.

By air-bottles I mean a confined space containing air, which air equalizes the flow of liquid 15 from the pump.

What I claim and desire to secure by Letters Patent is:

1. In a pumping apparatus, a casing including opposed cylindrical side walls and end walls 20 forming a pump chamber, one of the end walls having an inlet port for supplying fluid to said chamber, said chamber having an outlet at its top, an extension on said casing communicating with the pump chamber through said inlet port 25 and forming a fluid supply chamber, a constantly open by-pass at the top of the pump chamber providing communication between the outlet side thereof and the supply chamber, a pump of the oscillating piston type in said pump chamber, 30 said by-pass consisting of a laterally perforated tube extending across the pump chamber and having its perforations screened, the tube being closed at one end and open at the other end into said supply chamber.
  - 35 2. In a pumping apparatus, a casing including opposed cylindrical side walls and end walls forming a pump chamber, one of the end walls having an inlet port for supplying fluid to said chamber, said chamber having an outlet at its top, an extension on said casing communicating with the pump chamber through said inlet port 40 and forming a fluid supply chamber, a constantly open by-pass at the top of the pump chamber providing communication between the outlet side thereof and the supply chamber, a pump of the oscillating piston type in said pump chamber, said by-pass consisting of a laterally perforated tube extending across the pump chamber and having its perforations 45 screened, the tube being closed at one end and opening at the other end into said supply chamber, a supply pipe extending upwardly into the supply chamber to terminate adjacent the top thereof.
  - 50 3. In a pumping apparatus, a casing including opposed cylindrical side walls and end walls forming a pump chamber, one of the end walls having
- 25 30 35 40 45 50 55
- 20 25 30 35 40 45 50
- 20 25 30 35 40 45 50
- 25 30 35 40 45 50
- 20 25 30 35 40 45 50
- 25 30 35 40 45 50

an inlet port for supplying fluid to said chamber, said chamber having an outlet at its top, an extension on said casing communicating with the pump chamber through said inlet port and forming a fluid supply chamber, a by-pass at the top 5 of the pump chamber providing communication between the outlet side thereof and the supply chamber, a pump of the oscillating piston type in said pump chamber, said by-pass consisting of a laterally perforated tube extending across the 10 pump chamber and having its perforations screened, the tube being closed at one end and opening at the other end into said supply chamber, said pump comprising a stationary member having sides straddling the inlet port, said sides 15 having fluid ports and check valves covering said ports, said check valves being arranged to open toward said pump chamber, and an oscillating member having piston blades oscillatable about the axis of the pump chamber with the blades 20 in contact at their radially outer ends with the cylindrical walls of said pump chamber, said blades having fluid ports and check valves covering said blade ports, said last named check valves 25 being arranged to open toward said outlet.

4. In a pumping apparatus, a casing including opposed cylindrical side walls and end walls forming a pump chamber, one of the end walls having an inlet port for supplying fluid to said chamber, said chamber having an outlet at its top, an extension on said casing communicating with the pump chamber through said inlet port and forming a fluid supply chamber, a by-pass at the top 30 of the pump chamber providing communication between the outlet side thereof and the supply chamber, a pump of the oscillating piston type in said pump chamber, said by-pass consisting of a laterally perforated tube extending across the pump chamber and having its perforations 35 screened, the tube being closed at one end and opening at the other end into said supply chamber, a supply pipe extending upwardly into the supply chamber to terminate adjacent the top thereof, said pump comprising a stationary member having sides straddling the inlet port, said 40 sides having fluid ports and check valves covering said ports, said check valves being arranged to open toward said pump chamber and an oscillating member having piston blades oscillatable about the axis of the pump chamber with the 45 blades in contact at their radially outer ends with the cylindrical walls of said pump chamber, said blades having fluid ports and check valves covering said blade ports, said last named check valves 50 being arranged to open toward said outlet.

ARTHUR JOHN ADAMS.
